UNITED STATES PATENT OFFICE.

PARK A. HERR, OF SAYBROOK, NEW JERSEY, ASSIGNOR TO THE SINGER MANUFACTURING COMPANY, A CORPORATION OF NEW JERSEY.

SEWING-MACHINE.

1,329,763.

Specification of Letters Patent. Patented Feb. 3, 1920.

Application filed December 31, 1915. Serial No. 69,692.

To all whom it may concern:

Be it known that I, PARK A. HERR, a citizen of the United States, residing at Saybrook, in the county of Union and State of New Jersey, have invented certain new and useful Improvements in Sewing-Machines, of which the following is a specification, reference being had therein to the accompanying drawings.

10 This invention relates to improvements in sewing machines of that type in which the needle may be vibrated laterally to produce "zigzag" stitches, and it has for its object to provide an organized structure especially adapted for sewing heavy work, and capable 15 of producing stitches extending transversely of the direction of feed of a length of two and one-half inches or more.

In the embodiment of the invention hereinafter more fully described, the needle-bar is reciprocated in two vertically disposed sleeves slidingly mounted upon the overhanging arm of the machine and given bodily movements to laterally vibrate the 25 needle-bar. The said sleeves receive their movements through connection with a rocker which also acts to impart bodily movements to a shuttle and means for accelerating the oscillation of the shuttle. The 30 combined bodily movement and accelerated oscillatory movement of the shuttle compensates for the extreme lateral vibrations of the needle, whereas the acceleration alone or, if desired, the bodily movement alone 35 of the shuttle, may be utilized to compensate for short lateral vibrations of the needle. To compensate for the lateral throw of the needle toward the beak of the shuttle, in which case the shuttle thread in its cast-off 40 position will not lead in a straight line to the work, but will be turned back in the form of a loop embracing the dead limb of the needle-loop which results in the subsequent twisting of the needle-loop about the 45 shuttle-thread, the shuttle-driver is utilized as a pull-off and positioning device for the shuttle-thread, and thus acts to insure the proper formation of the stitch.

In the accompanying drawings, Figures 50 1 and 2 are perspective views of a machine embodying the preferred form of my improvement, showing the mechanism for reciprocating the needle-bar and imparting

to it lateral vibratory movements, Fig. 3 is a bottom plan view of the sewing machine 55 bed with the mechanism for driving the shuttle in its raceway and imparting to its carrying frame reciprocating movements, Fig. 4 is a sectional elevation of the sewing machine bed illustrating more in detail the 60 driving connections for the shuttle carrying frame, Fig. 5 is a detailed elevation of the shuttle and its raceway in extreme lateral needle position; and Figs. 6, 7, 8 and 9 are detailed perspective views of the shuttle 65 showing the method of forming stitches and Fig. 10 is a perspective view illustrating the action of the shuttle-thread pull-off.

The improvements are embodied in a machine frame comprising the bed A to 70 which is secured the standard B merging into the usual overhanging arm C provided with the head D. The main or driving shaft 1 of the machine extends lengthwise of the overhanging arm C and has secured thereon 75 at one end the balance-wheel 2 and grooved belt-pulley 3, while the opposite end of the shaft has fixed thereon the cam disk 4 which is utilized to impart reciprocatory motion to the needle-bar 5 and also to actuate the 80 take-up 6.

Parallel with the needle-bar 5 and journaled in the head D is the press-bar 7 having fixed thereon at its lower end the split shank 8 of presser-foot 9 formed with the 85 needle receiving slot 10. Suitable means are provided for regulating the pressure of the presser-foot 9 upon the work. In this instance the presser-bar has clamped thereon at its upper end by means of the set-screws 90 11 a block 12 provided with the vertically extending spaced ears 13 supporting between them the cross-pin 14 between which and the upper wall of the block is fitted the forward end of a plate-spring 15 having its rearward end apertured to fit upon a stud-screw 16 provided with the adjusting nut 17 and stop-nut 18 whereby the said rearward end of the spring 15 may be raised or lowered. Midway of its length the spring 15 is received within the horizontal rectangular aperture 19 of a collar 19 formed with the depending spaced ears 20 apertured to receive a pin 21 serving to connect the collar with the upper end of a link 22, the lower 100 105 end of said link being connected by means

2
of a crank-stud 23 on the end of a rock-shaft 24 adapted to be manipulated by means of a lever 25 to raise or lower the spring centrally of its length and thereby throw 5 the pressure thereof upon the presser-bar or relieve the pressure of the spring and subsequently elevate the bar to move the presser-foot above the work, the said mechanism being similar to that shown and described in the patent to Charles M. Horton, 10 No. 1,279,112, issued September 17, 1918.

The needle-bar is fitted to reciprocate within the vertical sleeves 26, each sleeve being carried at the end of a short shaft 26* 15 fitted to slide within apertures *a* formed in the head *D* of the overhanging arm. Clamped upon the needle-bar midway of its length by means of the set-screws *s* is a collar 27 having fixed thereon a block 28 fitted 20 to slide within the channel 29* of a reciprocating driving member 29 operatively connected by means of the link 30 and crank-stud 31 with cam disk 4 carried at the end of the driving shaft 1. To guide the driving 25 member 29 in its movements, the latter is provided with a projecting rectangular lug 32 which slides within the vertical slot 33 formed in the guide-arm 34 secured by means of screws 35 upon the head *D*.

30 The means for imparting lateral vibratory movements to the needle-bar comprise the vertical rock-shaft 36 journaled in the bosses 37 projecting from the overhanging arm *C* and carrying at its ends the crank-arms 38 connected by means of the upper link 39 and lower link 40 with the sleeves 26. The rock-shaft 36 has clamped thereon at its upper end the sleeve 41 of a crank-arm 42 which receives motion by means of link 43 from a 35 rock-arm 44 fulcrumed at *f* upon the standard *B* and actuated by a cam-wheel 45 through the adjustable link 46 and other connections now to be described.

The cam-wheel 45 is fixed upon the outer 45 end of a short shaft 46* extending transversely of the overhanging arm *C*, and journaled in suitable bearing bosses afforded by the latter. The cam-wheel is formed integral with the gear-wheel 45* driven by means 50 of pinion 47 on the end of a short shaft 48 also journaled transversely of the overhanging arm *C* and operatively connected within the said arm, by means of the spiral gears 49 and 50, with the main shaft 1. The cam-wheel 45 is a pattern cam formed with a cam slot 51 of the desired formation to act upon a stud 52 carried by a segment lever 53 fulcrumed at 54 upon the overhanging arm *C*, and embraced by the clamping block 55 55 pivotally connected at 56 with the link 46 and provided with the clamping screw-stud 57 which serves to secure the block 55 in its adjusted position.

It will be seen that by means of the afore- 60 said connections the needle-bar will be vi-

bated laterally according to the character of the pattern cam and the adjustment between said cam and link 46 and that reciprocating endwise movements will be imparted to the needle-bar from the main shaft 70 by means of a cam disk 4 and link 30.

The toothed work-engaging portions of the feed-dog 58 project through apertures formed in the throat-plate 59, the dog being supported upon the feed bar frame 60 which receives reciprocatory feeding movements from feed-rocker 61 driven from the main-shaft by means of the eccentric 62, pitman 63 and crank-arm 64, rising and falling movements being imparted to the feed-dog 75 by means of the feed-lift rocker 65 having a rock-arm 65* connected to the feed-bar frame and a crank-arm 66 formed as a yoke to embrace and receive motion from an eccentric 67 carried by the rock-shaft 68, the latter 80 being journaled in the bearing bosses 69 and 70 depending from the bed *A*, and being driven by crank *e* on the main-shaft 1 through pitman *e**, rocker 1, link 1*, and crank-arm 68*.

90 The shuttle 71 is fitted to oscillate within the raceway 72, the latter being secured to a carrying frame 73 mounted to slide upon the shaft 74 fixed within an aperture formed in bearing boss 70 and a second aperture formed in a depending portion *A** of the bed. The shuttle is oscillated by means of the driver 75 the latter being of the usual construction with an exception to be herein-after set forth. The driver is carried upon the end of a short shaft 76 upon which is secured the gear-wheel 77 meshing with a second gear-wheel 77* carried at the end of a shaft 78 also journaled within the bearing boss 70 and provided with the wide pinion 100 79 meshing with pinion 80 at one end of a sliding sleeve 81. The sleeve 81 is slidingly mounted upon a second sleeve 82 fixed upon a rock-shaft 68 and is formed with an inclined slot entered by a stud *a*' projecting 110 from said sleeve 82. By means of stud *a*' the sleeve 81 is caused to partake of the oscillatory movements of shaft 68 and thereby transmit operative movements to the shuttle.

115 It will be understood that when the clamping block 55 is in its extreme upper position on the rock-arm 53 that the latter will move idly and no endwise movement will be imparted to link 46 and hence rocker 44 will remain motionless, the reciprocation of the needle in its unchanging lateral position causing the formation of straightaway stitches. When clamping block 55 is adjusted on the rock-arm 53 to a position below its axis of movement, lateral movements 120 will be transmitted to the needle bar and it will become necessary to modify the action of the shuttle or bodily move the same in order that its beak may register with the needle eye in its various positions.

As illustrated by Fig. 5 a vibration of the needle, in the present embodiment of the invention, within the points $x-x'$ may be compensated for by acceleration of the shuttle, it being understood that when the needle is vibrated beyond the said points the beak of the shuttle will pass the needle below loop-seizing position.

The sleeve 81 constitutes one of the primary members of the mechanism for accelerating and retarding the movement of the shuttle-beak, or, in other words, altering the amplitude of its operative movements to maintain its correct relation with the needle-eye for seizure of needle-loops in the laterally spaced positions which the needle assumes during the formation of zig-zag stitches.

The means for imparting axial movements to the sleeve 81 are primarily those employed to impart lateral movements to the needle-bar. The rock-lever 44 which receives motion from the cam-wheel 45 is formed with a depending arm 44^x which projects below the bed-plate and has pivotally connected thereto at 83 one end of a link 84, the opposite end of the link being connected to a crank-arm 85 secured upon one end of a short rock-shaft 86 journaled in a bearing boss 86^x projecting from the under face of the bed A, the said rock-shaft being provided with a second crank-arm 87 connected by means of link 88 with a yoke member 89 which embraces the reduced end of sleeve 81. It will be seen that the motion of rock-lever 44 in transmitting lateral movement to the needle-bar will, through link 84, rock-shaft 86 and link 88 transmit sliding movements to the sleeve 81 during the oscillation of the latter, thereby imparting an accelerated or retarded oscillation to shaft 78 according to the direction in which the sleeve 81 is axially moved.

Means are provided for bodily moving the shuttle simultaneously with the bodily lateral movements of the needle-bar, so that in relatively short lateral movements of the needle-bar either the shuttle acceleration means or the expedient of bodily moving the shuttle may be employed. The means for bodily moving the shuttle comprises the rock-shaft 86, crank-arm 87 and a link 90 connecting the shuttle carrying frame 73 with the crank-arm 87, so that as the rock-shaft 86 transmits, by means of link 88, axial movement to the sleeve 81 to accelerate the shuttle beak, the said rock-shaft 86 will also transmit bodily movements to the shuttle-carrying frame.

Whenever it is desired to dispense with the acceleration of the shuttle and yet continue the bodily lateral movements thereof it is only necessary to disconnect the link 88 and connect the links 39 and 40 to the rock-

5 arms 38 at z . Also when it is desired to dispense with the bodily lateral movements of the shuttle and continue the acceleration thereof it is only necessary to disconnect the link 90, and connect the links 39 and 40 as aforesaid.

Again referring to Fig. 5 it will be seen that when the needle is vibrated beyond the points $x-x'$, the acceleration of the shuttle alone will not enable its beak to properly register with the needle-loop, and that it will be necessary to bodily move the shuttle, especially when coarse thread is used in sewing heavy work, in which case it is necessary that the beak enter the loop at a point above the eye of the needle not less than $\frac{1}{4}$ ". Therefore by providing means for accelerating the movement of the shuttle and simultaneously imparting a bodily lateral movement to the shuttle, ample provision is made for the coöperation of the shuttle with the needle whatever may be the length of vibration of the latter, and also the bodily movement of the shuttle is reduced to a minimum. In the relationship of the parts illustrated in the drawings, and particularly Fig. 90 5, the acceleration of the shuttle and the bodily movement thereof are of equal effect in insuring the coöperation of the shuttle beak and the needle when the latter is vibrated beyond the points $x-x'$ and within the points $y-y'$.

When the needle moves to the left, or toward the beak of the shuttle the effect in the formation of a stitch is the same as that obtained by reversing the feed in straight-away sewing, *i. e.* the thread in the cast-off position of the shuttle will not lead in a straight line to the work, but will be turned back in the form of a loop embracing the dead limb of the needle-loop, as illustrated in Fig. 6, the normal lead of the thread in the cast-off position being shown in Fig. 7. In such case when the take-up pulls upon the live limb of the needle-loop it will be turned by the abnormal lead of the shuttle-thread and subsequently will be twisted about the latter. The needle-loop in its first stage of movement under the action of the take-up will slip up the shuttle-thread to the position a shown in dotted lines Fig. 8 until, at the said point, by its twist it grips the shuttle-thread with considerable frictional force, so that in the continued action of the take-up it will pull upon the shorter lead of the shuttle thread *i. e.* that extending in the direction of the previously formed stitch, and the result will be that illustrated in Fig. 9. To remedy the aforesaid defective action of the stitch-forming mechanism a shuttle-thread engaging stud 91 is carried by the shuttle driver 75, so that in the reverse movement of the driver when the needle is moved laterally to its left hand position, Fig. 10, the stud will engage and pull off the thread from the shuttle until the shuttle-thread lies

in the position *b* Fig. 10 which closely approximates the lead of the thread shown in Fig. 7.

Having thus set forth the nature of the invention, what I claim herein is:

1. In a sewing machine, in combination, stitch-forming mechanism including a laterally vibrating needle and a circularly movable looper, and means for imparting to said looper a combined bodily and accelerated or retarded circular movement to insure the co-operation of the looper-beak and needle in all lateral positions of the latter. 70
2. In a sewing machine, the combination with stitch-forming mechanism including a laterally vibrating needle and a looper, of means for imparting to the looper an accelerated or retarded circular movement and also a bodily movement of less degree than the lateral movement of the needle. 75
3. In a sewing machine, the combination with stitch-forming mechanism including a laterally vibrating needle and a looper, of means for imparting to the looper a combined bodily and accelerated or retarded circular movement, and means adapted to permit the employment of either the acceleration or the bodily movement of the looper to insure its register with the needle within a field of vibration of the latter. 80
4. In a sewing machine, the combination with stitch-forming mechanism including a laterally vibrating needle and a looper, of means imparting to the looper an accelerated or retarded circular movement and also a bodily movement of less degree than the lateral movement of the needle, and means adapted to adjust simultaneously the vibration of the needle and the accelerated and bodily movement of the looper. 85
5. In a sewing machine, the combination with a frame, a needle-bar and a needle carried by the latter, of spaced bodily movable bearing members within which the bar is mounted for reciprocation, a projecting driving-connection fixed upon the bar, a reciprocatory driving-member formed with a groove to receive the said driving-connection, and means for alternately reciprocating the driving-member and laterally moving the bar relatively to said driving-member. 90
6. In a sewing machine, the combination with a frame and a needle-bar, of spaced sleeves affording bearings for the bar and bodily movable upon the frame, a slide-block clamped upon the bar, a driving-member formed with a groove to receive the said slide-block, a guiding element engaging said driving-member to limit its movement to reciprocation in a direction laterally of its said groove, actuating means for the driving-member, and means acting to vibrate the bar laterally. 95
7. In a sewing machine, the combination with a frame and a needle-bar mounted thereon for movement in transverse directions, an actuating shaft, means operatively connected with said shaft for laterally moving the needle-bar, a slide-block clamped upon the bar, a movable arm formed with a groove to receive the slide-block, means for limiting the movement of the arm to reciprocation in a direction laterally of its groove, a crank-stud on the shaft, and a link directly connecting said stud and the arm. 100
8. In a sewing machine, the combination with a frame, a needle-bar and means including a rocker for reciprocating the bar in transverse directions, of a looper, a looper actuating shaft, connections between the shaft and looper for imparting circular movements to the latter, a sleeve formed with an inclined slot, gears on and connecting the actuating shaft and sleeve, a second shaft receiving and having a pin engaging the slot of the sleeve, driving means for the second shaft, and means including the said rocker for imparting axial movements to said sleeve. 105
9. In a sewing machine, the combination with a needle-bar and means for imparting to the same reciprocatory movements in transverse directions, of a looper, means for imparting a normal circular movement to the looper, means for accelerating or retarding the normal circular movement of the looper, and connections driven by the last named means for imparting bodily reciprocatory movements to the looper. 110
10. In a sewing machine, the combination with a needle-bar and means for imparting to the same reciprocatory movements in transverse directions, of a looper, a movably sustained frame in which the looper is mounted, a driving shaft, a looper-actuating shaft, an axially movable sleeve connected to one shaft and having a pin and inclined slot connection with the other shaft, a rocker, an operative connection between the rocker and the looper frame, and an operative connection between the rocker and the sleeve. 115
11. In a sewing machine, the combination of a needle-bar and means for imparting to the same movements in transverse directions, of a shuttle, a shuttle-actuating shaft, a movable frame in which the shuttle and actuating shaft are journaled, a driving shaft geared to the shuttle actuating shaft, a rocker and a link connection between the rocker and the movable frame. 120
12. In a sewing machine, the combination with a frame and a needle-bar mounted on the frame for endwise and lateral shifting movement, of a looper and means for circularly moving the same, a rocker and a needle-bar shifting device connected therewith, a looper shifting device and a looper accelerating device each detachably connected with the rocker, and an adjustable connection between the needle-bar and its shift. 125

ing device adapted to compensate for the detachment of either the looper shifting device or the looper accelerating device.

13. In a sewing machine, in combination, 5 stitch-forming mechanism including a needle adapted to reciprocate in laterally spaced paths, a loop-taker having a loop-seizing beak and adapted to perform bodily lateral movements, means for laterally shifting said

needle and loop-taker different distances in 10 a given stitch-forming cycle, and means additional thereto for maintaining in said stitch-forming cycle substantially normal co-operative relation between the needle and loop-taker beak.

In testimony whereof I have signed my name to this specification.

PARK A. HERR.
